UNITED STATES PATENT OFFICE.

AARON JEDEL, OF NEWARK, DELAWARE.

PYROTECHNICAL DEVICE.

1,163,756.

Specification of Letters Patent. Patented Dec. 14, 1915.

Application filed April 9, 1915. Serial No. 20,328.

To all whom it may concern:

Be it known that I, AARON JEDEL, a citizen of the United States, residing at Newark, in the county of New Castle and State of Delaware, have invented new and useful Improvements in Pyrotechnical Devices, of which the following is a specification.

The invention relates to pyrotechnics, and has for an object to provide a pyrotechnical device of a simple construction, which can be cheaply manufactured and which can be safely and easily manipulated to produce sparkling pyrotechnical effects of variegated colors and designs.

The invention contemplates, among other features, the provision of a simple pyrotechnical toy which is preferably adapted to be manually manipulated to produce pyrotechnical effects in the nature of double pin-

wheels and the like.

The device further contemplates a toy which is in the nature of what is known in the pyrotechnical art as a sparkler and which, in this particular instance, is commercially known as an airio-wheel, in that it produces a pyrotechnical effect in which the sparkling devices will be in the nature of double pinwheels, and the sparkling effect can be either of a star shape or chrysanthemum emanation, or wherein the effect produced will simulate two fiery rotating bodies which can be relatively spaced as to the circles of light or pyrotechnics which are produced.

The invention still further embodies various improvements over patents granted to me May 26, 1908, No. 888810; No. 1067520, of July 15, 1913, and 1110205, of September 8, 1914.

In the further disclosure of the invention reference is to be had to the accompanying drawings, constituting a part of this specification, in which similar characters of reference denote corresponding parts in all the views, and in which:

Figure 1 is a plan view of a wire of which the supporting device is formed; Fig. 2 is a similar view of the structure shown in Fig. 1, with portions thereof coated with the pyrotechnical substances or elements; Fig. 3 is a plan view of the pyrotechnical device as completed; Fig. 4 is a plan view of a slightly modified form of supporting member and holder in their initial stages; Fig. 5 is a view of the construction shown in Fig. 4, with the ends of the supporting member and

an end of the holder covered with the pyrotechnical substance or element; Fig. 6 is a plan view of the completed form of the modified structure, parts of which are shown in Figs. 4 and 5; and Fig. 7 is a plan view of a slightly modified form of structure.

Referring to the views, and more particularly to Figs. 1 to 3, inclusive, I provide a single piece of wire 10 which is looped to form a parallel portion 11, with the body portion of the wire forming a supporting member 12 to support pyrotechnical substances or elements 13 which are formed by a pyrotechnical compound or mixture into which the ends of the supporting member 12 are dipped, thus coating the ends of the supporting member 12 with the substance or element. It will be noted by reference to Fig. 2 that the looped portion of the wire 10 is coated by one of the pyrotechnical substances or elements and the portion 11 of the wire 10 is bent laterally of the supporting member 12 adjacent the inner end of one of the pyrotechnical elements upon said wire to form a holder or handle 14.

It will be understood that the wire 10 is of a readily yielding nature and can be easily bent and that after the wire has been formed as shown in Fig. 1 the ends are dipped to coat the ends of the body of the wire and the end portion of the holder with the substances or elements forming the pyrotechnical part of the invention, the handle being formed by bending a part of the portion 11 laterally of said portion and the supporting member 12 so that when the handle 14 is subsequently held in the hand and rotation imparted to the entire article, the pyrotechnical elements having been previously ignited, there will result a pinwheel effect and which I preferably term an airio-wheel, the simulation being that of an illuminated and brilliantly burning inner circle and a similar larger outer circle, this being due to the rotation of the article about the handle 14 and which handle is offset from the center of the wire 10 so as to provide the desired leverage to permit of rapidly rotating the device.

In Figs. 4, 5 and 6 I disclose a slightly modified form of my invention and in which I disclose a supporting member 15 and a holder 16, each being formed of a single piece of wire, with the ends of the member 15 and an end of the member 16 coated by the pyrotechnical substances or elements

18 mentioned heretofore, a portion of the holder 16 being bent to form the handle or laterally extending part 17. It will be seen by referring to Figs. 3 and 6 that portion 5 of the holder extends parallel to the supporting members 12 and 15 in the preferred and modified forms, and it will be clearly understood that in the manufacture of the articles mentioned I may bend the wire 13 forming the holder so as to have a portion extend laterally as shown in Figs. 3 and 6 or I may permit it to remain as shown in Figs. 2 and 5 of the preferred and modified forms, leaving it to the purchaser to bend 15 the parts 11 and 16 which form the holders.

In Fig. 7 I disclose a modified form of the construction shown in Fig. 1 and in which instance, instead of bending the holder indicated by the numeral 18, I bend 20 the supporting member 19 with respect to the holder so that whereas in the constructions shown in Figs. 3 and 6 the handle or holding portion is bent and the supporting member remains straight, in the construction 25 shown in Fig. 7 the handle or holding portion remains straight and the supporting member is bent to have a laterally extending part, the holder in the last mentioned instance lying throughout in axial alignment with one of the pyrotechnical 30 elements indicated by the numeral 13, whereas in the construction shown in Figs. 3 and 6 the supporting members lie in axial alignment with both pyrotechnical elements. Therefore, in the constructions shown in 35 Figs. 3 and 6, when the pyrotechnical elements are ignited and the entire article subjected to rotation, there will appear two illuminated circles of light, whereas in the construction shown in Fig. 7 there will 40 merely appear one circle of light and a center of blazing fire.

I preferably use a composition for the pyrotechnical elements which may consist 45 of steel and aluminum filings and starch, with a dye or coloring matter when the latter is desired, and it will be understood that the various forms of wire constructions shown in the views are dipped into 50 the pyrotechnical compound or substance so as to coat ends of the wire constructions and in each instance it will be seen that there is provided a supporting member and a holder. Now referring to Figs. 4, 5 and 55 6 it will be seen that one of the pyrotechnical elements, namely, the one shown at the left in Figs. 5 and 6, forms the binder or connecting means between the two pieces of wire forming the supporting member 15 60 and holder 16 so that this pyrotechnical element is not only used as a means of illuminating but primarily, and in the manufacture of the article, constitutes the binding medium for the two pieces of wire forming 65 the article. So also in Figs. 1, 2 and 3 it

will be noticed that although the holder 14 is an integral part of the supporting member 12, its portion 11 being formed by looping the wire 10, the pyrotechnical element shown at the left in Figs. 2 and 3 also in 70 this instance forms a binder to prevent undue separation of portions of the supporting member with respect to the holder and maintains a portion of the holder in parallel relation to the supporting member, 75 and it will be clearly seen that in all the views there are portions of the holder in parallel relation to portions or the entireties of the supporting members.

It will be noted that in all of the forms 80 described and set forth herein there must be a rotation of the stem or holder with respect to the hand grasping the holder in order to obtain the desired result and impart to the article a rotary movement, this being 85 done by imparting a whirling or turning movement to the hand. The holder must therefore be rotated with respect to the hand in order to produce the rotation of the pyrotechnical members to effect the desired 90 result.

Although I am aware that various forms of pyrotechnical devices other than those which I have patented, as stated heretofore, have been used, and which produce circular 95 or pin-wheel effects, I aim to provide a device which can be cheaply manufactured in that the parts forming the devices are of wire which can be readily bent into the desired shape. Further, that the devices described are of such simple construction that they can be easily operated and, as mentioned heretofore, in the sale of the articles upon the market, the holder can be formed to extend laterally with respect to the supporting member when the devices are mounted or in order to permit of packing a large number of the devices in a box, the holder can be permitted to remain in its initial state as shown in Figs. 2 and 5 and be subsequently bent by the persons purchasing 105 the article.

Attention is particularly called to the slight space between the supporting member and holder at the point of formation of 115 the lateral part of the holder or at the point where the supporting member extends laterally to the holder, and it will be clearly seen that by having the holder spaced with respect to the supporting member there is 120 less liability of the holder becoming heated due to conduction of heat along the wire when the pyrotechnical elements have been ignited and the article is in use, and that if the holder were wrapped around or in 125 direct contact with the supporting member at the point of formation of the holder, the tendency of the conduction of heat to the holder would be so great as to make it almost impossible for the operator to grasp 130

the holder by the hand after the pyrotechnical elements have been ignited and are burning toward the center of the supporting member.

5 Having thus described my invention, I claim:

1. A pyrotechnical device comprising a supporting member, a holder and a pyrotechnical element forming a binder for portions of said supporting member and holder.

10 2. A pyrotechnical device comprising a supporting member, a holder disposed at an angle to said supporting member, and a pyrotechnical element forming a binder for 15 said supporting member and holder.

3. A pyrotechnical device comprising a supporting member, a holder, and a pyrotechnical element encircling portions of said supporting member and holder.

20 4. A pyrotechnical device comprising a supporting member, a holder and a pyrotechnical element encircling portions of said supporting member and holder and forming a binder therefor.

25 5. A pyrotechnical device comprising a supporting member, a holder and a pyrotechnical element binding adjacently disposed portions of said supporting member and holder.

30 6. A pyrotechnical toy comprising a supporting member, a holder, and a pyrotechnical element encircling adjacent ends of said supporting member and holder.

35 7. A pyrotechnical device comprising a supporting member and a holder, said supporting member and holder having parallel portions, and a pyrotechnical element connecting said portions.

40 8. As a new article of manufacture, a pyrotechnical device comprising a wire having coated and uncoated portions, and a handle bound by the coating to the coated portion of the wire and having a portion extending parallel to and in spaced relation to the uncoated portion of said wire.

45 9. As a new article of manufacture, a py-

rotechnical device comprising a wire having coated and uncoated portions, and an integral handle bound by the coating to the coated portions of the wire and having a 50 portion extending parallel to and in spaced relation to the uncoated portion of said wire.

10. As a new article of manufacture, a pyrotechnical device comprising a wire having 55 coated and uncoated portions, and a handle having a portion bound by the coating to the coated portion of the wire and extending parallel to and in spaced relation to the uncoated portion of said wire and a 60 portion extending laterally to the uncoated portion of said wire.

11. A pyrotechnical device comprising a wire having coated and uncoated portions, and a handle comprising a grip portion and 65 a connecting portion, the latter being bound by the coating to the coated portion of the wire, said connecting portion being in part free from connection with and disposed parallel with and in spaced relation to the 70 uncoated portion of the wire.

12. A pyrotechnical device comprising a wire having coated and uncoated portions, and a handle integral with said wire, said handle comprising a grip portion and a connecting portion uniting said grip portion to the wire, said connecting portion extending parallel with and in spaced relation to the uncoated portion of said wire. 75

13. A pyrotechnical device comprising a 80 wire having coated and uncoated portions, and a handle comprising a grip portion and a connecting portion, the latter being bound by the coating to the coated portion of the wire. 85

In testimony whereof I affix my signature in presence of two witnesses.
